(57) **CLAIM**

The ornamental design for a golf rangefinder as shown and described.

DESCRIPTION

FIG. 1 is an elevated front-left view of a golf rangefinder according to a first embodiment of the invention golf rangefinder;

FIG. 2 is a front view of a golf rangefinder according to the first embodiment of the golf rangefinder;

FIG. 3 is a back view of a golf rangefinder according to the first embodiment of the golf rangefinder;

FIG. 4 is a right side view of a golf rangefinder according to the first embodiment of the golf rangefinder;

FIG. 5 is a left side view of a golf rangefinder according to the first embodiment of the golf rangefinder;

FIG. 6 is a top view of a golf rangefinder according to the first embodiment of the golf rangefinder;

FIG. 7 is a bottom view of a golf rangefinder according to the first embodiment of the golf rangefinder;

FIG. 8 is an elevated rear-right view of a golf rangefinder according to the first embodiment of the golf rangefinder;

FIG. 9 is an elevated front-left view of a golf rangefinder according to a second embodiment of the golf rangefinder;

FIG. 10 is a front view of a golf rangefinder according to the second embodiment of the golf rangefinder;

FIG. 11 is a back view of a golf rangefinder according to the second embodiment of the golf rangefinder;

FIG. 12 is a right side view of a golf rangefinder according to the second embodiment of the golf rangefinder;

FIG. 13 is a left side view of a golf rangefinder according to the second embodiment of the golf rangefinder;

FIG. 14 is a top view of a golf rangefinder according to the second embodiment of the golf rangefinder;

FIG. 15 is a bottom view of a golf rangefinder according to the second embodiment of the golf rangefinder;

FIG. 16 is an elevated rear-right view of a golf rangefinder according to the second embodiment of the golf rangefinder;

FIG. 17 is an elevated front-left view of a golf rangefinder according to a third embodiment of the golf rangefinder;

FIG. 18 is a front view of a golf rangefinder according to the third embodiment of the golf rangefinder;

FIG. 19 is a back view of a golf rangefinder according to the third embodiment of the golf rangefinder;

FIG. 20 is a right side view of a golf rangefinder according to the third embodiment of the golf rangefinder;

FIG. 21 is a left side view of a golf rangefinder according to the third embodiment of the golf rangefinder;

FIG. 22 is a top view of a golf rangefinder according to the third embodiment of the golf rangefinder;

(Continued)

FIG. 23 is a bottom view of a golf rangefinder according to the third embodiment of the golf rangefinder; and, FIG. 24 is an elevated rear-right view of a golf rangefinder according to the third embodiment of the golf rangefinder. The broken line showing of the golf rangefinder is for the purpose of illustrating environmental portions of the golf rangefinder and forms no part of the claimed design.
